 Falls, N. Y., a corporation of New York

Application August 16, 1940, Serial No. 352,923

6 Claims. (Cl. 68—20)

My invention relates more particularly to apparatus for cleaning fabrics, such as clothing, by subjecting them to the action of solvents such as volatile solvents.

One object of my invention is to provide a simple, compact, self-contained apparatus comprising a cleaning element, a drying element, a deodorizing element, a filtering element for the solvent and a distilling element for the solvent.

A further object of my invention is to provide an apparatus that alternately soaks and rinses the fabrics in rapid succession.

Another object of my invention is to provide an apparatus that shall be substantially vapor tight and will ordinarily not permit fumes of cleaning fluid to escape into the room, to the detriment of the health of persons operating the apparatus.

Still another object of my apparatus is to provide means for distilling the solvent requiring no supervision during the process.

Referring to the drawings:

Fig. 1 is a front elevation of my apparatus.

Fig. 2 is an end elevation of my apparatus seen from the distilling end or right side in Fig. 1.

Fig. 3 is an end elevation of my apparatus seen from the filtering end or left side in Fig. 1.

Fig. 4 is a rear elevation.

Fig. 5 is a plan view.

Fig. 6 is a front elevation in section along line *a—a* of Fig. 5.

Fig. 7 is an end elevation in section along line *b—b* of Fig. 5, seen from the right end in Fig. 1.

Fig. 8 is a sectional elevation of the filter along the line *c—c* of Fig. 5.

Fig. 9 is a perspective view of the filter assembly, partly broken away to show the interior construction.

Fig. 10 is a perspective view of one of the filter leaves.

Fig. 11 is a perspective view of the sludge drawer which forms part of the filter element.

Fig. 12 is an enlarged side elevation of the two driving motors, partly broken away to show the driving connection between the two motors.

Fig. 13 is an end elevation of the motors, partly broken away to show further details of the aforesaid connection.

Referring to Figs. 1 to 7:

The cleaning and drying assembly comprises washing cylinder 1 in its housing 2, 3, 4, 5; overhead solvent reservoir 6 comprising top 7, bottom 8 and walls 9; underneath solvent receiving and storage tank 10, comprising top 11, bottom 12 and walls 13; solvent pump 14; blower 15; filter 16;

motors 17 and 18 which drive washing cylinder 1 at low and high speed respectively, and motor 19, which drives pump 14 and blower 15.

Washing cylinder 1 is mounted on shaft 20, 5 extending transversely of the housing, i. e., front to rear, and supported at its ends by bearings 21, which are carried by front and rear walls 4 and 5 of the housing. Between the ends of washing cylinder 1 and walls 4 and 5 the clearance is 10 sufficient to avoid rubbing but not to permit free flow of air to the blower 15. The cylindrical shell of washing cylinder 1 is perforate. Its rear end is closed by plate 22. Its front end is closed by plate 23, through which openings are provided 15 for introduction and withdrawal of the materials to be cleaned. The interior of the washing cylinder is divided by radial partitions 24 into compartments, preferably three in number. An opening is provided in end plate 23 to give access 20 to each compartment. These openings are normally closed by doors 25, hinged at 26 and provided with means 27 for securely locking them. Registering with doors 25, one at a time, when the door is in the position of the uppermost door 25 shown in Fig. 6, is an opening 28 through front wall 4 of the housing. Opening 28 is normally closed by door 29, sliding in guides 30. Door 29 may be securely locked by turning its handle 31, so as to form a vapor tight closure with front wall 4 of the housing.

Reservoir 6 is secured to housing 2, 3, 4, 5 by flanges 33. The housing is divided by flanges 34 into upper and lower sections, the latter of which is preferably welded to top plate 11 of tank 10. 35 Housing 2, 3, 4, 5, is provided with a V bottom formed by plates 35, making an obtuse angle with each other. The apex of the V lies directly beneath the axis of the washing cylinder and is parallel therewith. At the left side of the lower 40 section of the housing are two vertical baffles 36, 37, parallel with each other and with side wall 2. The space between baffles 36 and 37 forms a passage which is open at the top but closed at the bottom except for passage 38. Solvent may flow 45 freely outward through passage 38, but reverse flow is prevented by check valve 39. Solvent issuing through check valve 39 is delivered through passage 40 into tank 10. Tank 10 is divided by baffle 41 into two compartments, which 50 however are in free communication with each other through passage 42. The compartment to the left of baffle 41 houses pump 14, the intake of which dips into sump 43. Pump 14 delivers through pipe 44 to filter 16, to be described in detail later. The filtered solvent returns through 55

pipe 45 to reservoir 6 from which overflow pipe 46 permits excess solvent to return to tank 10. Reservoir 6 is also vented to tank 13 above the liquid level in both tanks by means of pipe 47. Reservoir 6 is provided with sight glass 48 (Fig. 3) by means of which the level of the solvent within it can be noted.

The upper edge of baffle 37 stops short of the level of flange 34. From the level of the upper edge of baffle 37 the lower section of the housing forms a vat 49 for solvent, into which the washing cylinder dips for about one third of its diameter.

Glass window 50 is provided for observation of the liquid level and circulation within housing 2, 3, 4, 5 and more particularly within vat 49 just referred to.

The upper section of housing 2, 3, 4, 5 is provided with baffles 51 and 52, one at each side of washing cylinder 1. Between the lower edges of these baffles and the cylinder the clearance is sufficient to avoid rubbing, but insufficient to permit free flow of air.

Through walls 2 and 3 of the housing are circular openings 53 and 54, adapted to be closed by dampers 55, 56 respectively. Opening 54 communicates through air duct 57 with the intake of blower 15, this blower being housed in scroll 58 and delivering air through discharge opening 59 (Fig. 4), which is preferably of rectangular cross section.

Opposite opening 54, in the wall of air duct 57 is a similar opening 60, adapted to be closed by damper 61. Movement of dampers 55, 56 and 61 to the right in Fig. 6 closes passages 53 and 54 and opens passage 60. These dampers are mounted on a common shaft 62 actuated through a screw thread (not shown) by hand wheel 63.

Washing cylinder 1 is driven through driving pulley 64, driven pulley 65 and belt 66 at high speed by motor 18 or, alternatively, at low speed by motor 17, which drives through motor 18 and an overdrive clutch, to be described in detail later. When motor 18 is driving, motor 17 is disconnected by the overdrive clutch and does not turn.

Registering with opening 53 in wall 3 of the housing is ozonizer 67, which is provided with inlet shutters 68 and ozonizer tubes 69.

The ozonizer itself forms no part of the invention. Any efficient ozonizer may be used, but I prefer the type illustrated in which air is ozonized by radiant energy, largely ultra-violet light, through the walls, transparent thereto, of sealed glow discharge tubes, without contact of the air with an electric arc.

The operation of the apparatus is as follows:

When door 29 has been slid back to the open position the compartments of the washing cylinder are opened one by one and each compartment loaded with material to be cleaned, care being exercised to load all the compartments with approximately equal weights. Door 29 is then closed and locked and valve 70 opened by turning handle 71. With the dampers 55, 56 and 61 in the alternative position to that shown in Fig. 6, in which position openings 53 and 54 are closed and opening 60 open, motor 18 is started by moving switch 72 to the "on" position as in Fig. 1. This causes pump 14 to raise solvent from tank 10 through filter 16 to reservoir 6, whence it flows by gravity through valve 70 into housing 2, 3, 4, 5, delivering against the perforate shell of the cylinder and passing through it to the vat 49 at the bottom of the housing. Vat 49 becomes quickly

filled with solvent which overflows by passage 73 to tank 10. Motor 17 is then started by moving switch 74 into the "washing" position shown in Fig. 1. This causes washing cylinder 1 to revolve at slow speed (preferably about 28 revolutions per minute). During this operation the materials in the compartments of cylinder 1 are alternately immersed in solvent in vat 49 and then, as the compartment moves to the top position, rinsed by a heavy flow of clean filtered solvent flowing through valve 70. The materials are therefore soaked and rinsed with freshly filtered solvent many times a minute and thus cleaned more effectively, and in a shorter time, than if merely soaked in the solvent without rinsing or rinsed without soaking, in accordance with the practice of the prior art.

When the materials to be washed have been subjected to this treatment for a sufficient time, which usually amounts to about 5 minutes, valve 70 is closed and valve 75, Fig. 7, opened, by shifting handle 76, draining all the solvent from vat 49 back into tank 10. Motor 17 is then stopped by moving switch 74 into the "off" position and motor 18 started by moving switch 74 into the straight down or "extracting" position. The washing cylinder is thus spun at high speed (e. g., about 860 revolutions per minute) and the materials within it centrifuged, thus extracting from them in about 5 minutes all the solvent that can be removed in this way. Dampers 55, 56 and 61 are then shifted to the position shown in Fig. 6 and air drawn through the ozonizer, passage 53, the materials in the cylinder, passage 54, and air duct 57 to blower 15, whence it is discharged through opening 59 which is connected through air ducts not shown to the outer atmosphere. With the blower drawing air through the materials in the washing cylinder, these materials are dried in about four minutes.

Preferably the ozonizer is not energized until normal air has been drawn through the materials long enough to remove substantially all the more volatile constituents of the solvent, as it may be undesirable to subject the solvent to an oxidizing atmosphere for an unnecessarily prolonged period. When the materials have been thoroughly dried in this way, therefore, the ozonizer is energized by shifting electric switch 77 and ozonized air drawn through the materials until the relatively non-volatile constituents of the solvent, which are largely responsible for after odor, have been effectively oxidized.

Pilot light 78 gives visual warning when the ozonizer is energized, thus minimizing the likelihood of leaving the ozonizer energized when it is not wanted.

The ozone deodorizing feature is claimed in divisional application Serial No. 420,138, filed November 21, 1941.

It should be noted that during the washing operation air is being drawn through opening 53 and discharged through the blower and opening 59 to the outer air, thus ventilating the room, and that while the air is being drawn through opening 53 the room is likewise being ventilated.

It should also be noted that the solvent is continuously filtered during the washing operation.

It should likewise be noted that when dampers 55 and 56 are closed housing 2, 3, 4, 5; reservoir 6, tank 13; filter 16, etc., constitute a normally closed system, in which the ratio of volume occupied by air to volume occupied by liquid is sufficient to prevent the building up of a dangerous or inconvenient pressure at any tempera-

ture that can possibly develop in the apparatus under the conditions of use. Also it prevents the building up of a vacuum by cooling of solvent vapor, such as might collapse the apparatus. This is an important feature of my apparatus as it eliminates any necessity for providing a safety valve or vent to the atmosphere, which unless refrigerated, would occasion serious loss of solvent.

Referring to Figs. 6, 8, 9, 10 and 11:

These figures illustrate the filter and its accessories. The filtering element 103 removed from the rest of the assembly is illustrated in perspective in Fig. 10. This comprises a filter bag 104 of woven fabric, preferably cotton, adapted to be slipped over a steel supporting structure. The latter consists of a rectangular sheet of wire screen 105, heavy enough to be fairly rigid. The edge of the screen at one end is let into a slot extending through a plate 106, to which the screen is welded. Plate 106 is wider than the screen and longer than the screen is wide, so that it forms a flange at one end of the screen. The other three edges of the screen are capped by a thin strip of metal 107 which is folded over the edges of the screen and extends a short distance down each side. The purpose of this strip is to protect the filter bag from being punctured by the ends of the wires of the screen. The mesh of the screen itself affords passage for liquid that has passed through the filter bag. The liquid thus finds its way to the flange end of the filter element, where it passes out through slot 108. Eight of these filter elements are mounted in two banks of four each. The elements of each bank are parallel to each other. They are supported by plate 109 which is slotted to permit each element to drop into its position. The filter elements are spaced by steel frame 110. Filter bag 104 is flared outward beneath plate 106 so as to form a gasket between it and plate 109. The plates 106 of the filter elements are clamped against plate 109, with the flare of the filter bag between, so as to make a liquid tight joint therewith, by yokes 111. In Figs. 8 and 9 yoke 111 is partly broken away better to show adjacent parts. Each filter element 103 is provided with a handle 112 by which it may be lifted out when yokes 111 are removed. The whole assembly of filter elements is covered over by cover member 113. The flow of solvent is therefore through slots 108 to the space 133 beneath cover 113. From here the solvent returns through holes 134 to enclosure 135, with which exit pipe 45 is in communication. Enclosure 135 is preferably placed between the two banks of filter elements, which is not the plane of the section of Fig. 8. The intervening parts are therefore broken away to show some of the holes 134, as well as a part of enclosure 135, in section.

It should be noted that because of the fact that exit pipe 45 is connected to housing 118 below the flange of cover 113 this cover can be removed without disconnecting the pipe. The infeed of solvent is through pipe 44, which terminates in perforated nozzle 114. The discharge from the filter is through pipe 45. Shut-off valves 115 and 116 are provided in pipes 44 and 45 respectively for use when it becomes necessary to disassemble the filter. Sight glass 117 is provided in pipe 45 in order that the flow of solvent from the filter may be observed.

The side walls of the filter housing 118 are made corrugated, as these walls are liable to be subjected to a pressure of as much as 15 pounds

per sq. in. However, cover 113 and the flanged joint which it makes with filter housing 118, being on the low pressure side of the filter elements, is never subjected to a pressure of more than 3 pounds per sq. in. Gauge 119 is provided in order to show by the back pressure when the filter needs cleaning.

Filter bag 104 is not the filtering medium but only the support for it. The actual filtering medium is a layer of finely divided inert material, such as infusorial earth or "filter-aid," with which the bag becomes coated. This material is introduced into the solvent through hopper 120, by opening cover 121 which is normally locked by handle 122. Through hopper 120 the filtering material is delivered to the stream of solvent at the intake to pump 14. In this way it is quickly deposited on the filter bag.

When the filter has become much clogged with foreign matter this fact is evidenced by a rise in back pressure, as shown by gauge 119. To remedy this situation, during an interval between washing operations the solvent is pumped up into reservoir 6. Valve 115 is then shut off and valve 123 opened. The solvent flowing in the reverse direction through the filter by gravity then dislodges the cake of filter-aid or other filtering material which carries the foreign matter. This cake breaks off from the surface of the filter bags in pieces. These are caught by hopper 124 and directed into sludge drawer 125. This drawer is illustrated in perspective in Fig. 11. It is constructed in the form of an elongated box, with four side walls and two longitudinal partitions. The side walls are of a construction similar to that of filter element 103. That is to say, they are of wire screen 126 with edges covered by strips of metal 127, the whole being covered with fabric 128 similar to that used in the filter bags themselves. Therefore when the flow is reversed, the pieces of filter cake are caught in the sludge drawer, while the solvent passes through and returns by pipe 129 to tank 10. The purpose of the longitudinal partitions is to increase the surface through which the solvent may percolate in its reverse flow. During the normal operation of the apparatus the sludge drawer is closed, its flange 130 being bolted to flange 131 of the main filter body 118 so as to make a liquid-tight joint therewith. After the filter cake has been dislodged and caught in sludge drawer 125, and all the solvent returned to tank 10, the sludge drawer is unbolted, withdrawn by means of handle 132 and emptied.

It should be noted that in the normal operation of the filter just described, the solvent first fills sludge drawer 125 and the liquid level then rises until the entire housing below cover 113 is completely filled and every part of the filter surface is utilized; whereas if the flow were downward by gravity, which is common practice, the lower parts of the filter surface would be the most active and the upper parts would never become properly coated with filter-aid nor properly cleansed when the flow was reversed.

The filtering feature is claimed in divisional application Serial No. 420,137, filed November 21, 1941.

Referring to Figs. 8, 9, 12 and 13:

These figures illustrate the driving connection between motors 17 and 18, by which the two speed drive of the washing cylinder is secured without a gear shift. From these figures it will be seen that motor 17, through its shaft 79 and coupling 80, drives worm 81 (conventionally indicated),

which is mounted on shaft 82, carried by bearings 83. Worm 81 engages worm gear 84 (likewise conventionally indicated) which is a ring carried by bearing 85, which in turn is mounted on shaft 86 of motor 12. Worm gear 84 carries two driving pins 87 extending through it parallel to shaft 86. Upon pins 87 are mounted pawls 88, which engage ratchet wheel 89. Ratchet wheel 89 is keyed to shaft 86. Pawls 88 are spring pressed against ratchet wheel 89. When motor 17 is energized, it therefore drives motor 18 through worm 81, worm gear 84, pawls 88 and ratchet wheel 89; but when motor 18 is energized the pawls slip over the ratchet wheel and disengage motor 17, which therefore stands idle. The worm gear drive between motors 17 and 18 provides a very great speed reduction, which not only permits the washing cylinder to be driven at low speed by motor 17, when the cylinder is dipping into the solvent and high speed would be unnecessary and undesirable, but enables motor 17 to develop the relatively high torque necessary to drive the cylinder under these circumstances. It should be noted that this change from low to high speed is accomplished through the motor starting switches only, without any shifting of gears.

The possibility of motors 17 and 18 being started by inadvertence while door 29 is open, or door 29 being opened when the motors are running, is guarded against by pin 90 (Fig. 1) which is pushed downward through upper guide 30 when the handle of switch 74 is moved to the "washing" or "extracting" positions. If door 29 should be open, in which position it is slid to the left in Fig. 1, it interferes with pin 90 being pushed downward and thus prevents switch 74 from being moved to operating position. Similarly, when switch 74 is in operating position and pin 90 pushed downward, the latter interferes with door 29 being pushed to the left.

Referring to Figs. 1, 2 and 4 to 6:

During intermissions in the washing operation, as for example during the lunch hour or after a day's work, the solvent may be distilled. For this purpose, with valve 76 closed, the solvent is first pumped up by means of pump 44, operated as before described, until reservoir 6 is filled to the level of the overflow, at which level it holds about one-half of the entire charge of solvent. From reservoir 6 the solvent is allowed to return by gravity through the still to tank 10, which it does without supervision. The still comprises vaporizer 91 and condenser 92. Vaporizer 91 comprises an elongated vertical cylinder in the base of which are steam coils 93 and a float valve 94 controlling admission of solvent. Solvent is led from reservoir 6 to float valve 94 through pipe 95. The float valve serves to keep the liquid level constant in cylinder 91 so long as the supply of solvent to be distilled is sufficient for the purpose. Steam coils 93 are let into the base of the vaporizer through cover plates 96 and steam is admitted to, and condensate removed from them, by means of pipes 97. From time to time, sediment left behind by the distilled solvent is drawn off through valve 98 (Fig. 2). Sight glass 99 gives a visual indication of the liquid level in the vaporizer. The vapors from vaporizer 91 are conducted to condenser 92 through pipe 100. The condenser comprises an elongated vertical cylinder provided with conventional tube sheets at its ends and a battery of tubes 101 between them. Cooling water flows around these tubes. The water pipes for ad-

mission and removal of cooling water do not show in the figures. The cold water is of course admitted near the bottom of the column and the warm water removed near the top, so that the movement is counterflow with respect to the solvent. The vapors are condensed in the upper part of the tubes and the condensed solvent cooled in the lower part. The cold distilled solvent returns to tank 10 through trap 102.

10 It should be noted that when steam is shut off from coils 93, no liquid is evaporated in the still. Under these conditions float valve 94 remains closed and serves as the equivalent of a shut-off valve in pipe 95.

15 Make up solvent is introduced to the apparatus by removing hand hole cover 136 (Fig. 5).

Many modifications of my apparatus within the scope of the invention will suggest themselves to any person skilled in the art. I do not, therefore, wish to be limited to the exact mechanical 20 details illustrated. In the claims the word "cylindrical" is to be understood in its true mathematical sense, namely, a surface generated by a straight line moving parallel to itself. It is also to be understood that the expression "inclined" as applied to the axis of the washing cylinder means any angle having a sufficient horizontal component to enable the washing cylinder to dip beneath the surface of the solvent for a part of its rotation and emerge for the remainder.

I claim as my invention:

1. An apparatus for cleaning materials by means of volatile cleaning liquids comprising a liquid tight housing, an overflow for cleaning liquid part way of the height of said housing, defining in the lower portion of the housing a vat for cleaning liquid, a substantially cylindrical foraminous container for materials to be cleaned 35 rotatable about a substantially horizontal axis and dipping for a part only of its diameter into said vat, a tank adapted to receive and store cleaning liquid overflowing from said vat, means for causing relatively slow rotation of said container, and means for raising cleaning liquid from 40 said tank and delivering it by gravity against the outside of the unsubmerged portion of said container substantially directly above the axis thereof and through its perforations to its interior and thence to said vat.

2. An apparatus for cleaning materials by means of volatile cleaning liquids comprising a liquid tight housing, an overflow for cleaning liquid part way of the height of said housing, defining in the lower portion of the housing a vat for cleaning liquid, a substantially cylindrical foraminous container for materials to be cleaned 45 rotatable about a substantially horizontal axis and dipping for a part only of its diameter into said vat, a tank adapted to receive and store cleaning liquid overflowing from said vat, a reservoir above said housing, means for causing relatively slow rotation of said container, means for raising cleaning liquid from said tank to said 50 reservoir and means directing gravitational flow of cleaning liquid from said reservoir against the outside of the unsubmerged portion of said container and through its perforations to its interior and thence to said vat.

3. An apparatus for cleaning materials by means of volatile cleaning liquid comprising a vat adapted to receive materials to be cleaned, a reservoir adapted to deliver cleaning liquid through a valve-controlled passage to said vat, a 55 valve-controlled overflow for cleaning liquid from

said vat, a tank adapted to receive cleaning liquid overflowing from said vat, a valve controlled passage adapted to empty said vat into said tank, means for raising cleaning liquid from said tank to said reservoir, an unobstructed overflow for cleaning liquid from said reservoir directly to said tank and an unobstructed vent directly connecting the upper portions of said reservoir and tank; said reservoir, tank, overflows, vent and liquid-raising means forming a closed, vapor tight system when said valves are shut off.

4. An apparatus for cleaning materials by means of volatile cleaning liquid comprising a vat adapted to receive materials to be cleaned, a reservoir adapted to deliver cleaning liquid through a valve-controlled passage to said vat, a valve-controlled overflow for cleaning liquid from said vat, a tank adapted to receive cleaning liquid overflowing from said vat, a valve controlled passage adapted to empty said vat into said tank, means for raising cleaning liquid from said tank to said reservoir, an unobstructed overflow for cleaning liquid from said reservoir directly to said tank and an unobstructed vent directly connecting the upper portions of said reservoir and tank, a still adapted to receive cleaning liquid from said reservoir, and a condenser adapted to receive vapor from said still, condense the same and return it to said tank; said reservoir, tank, overflows, vent, liquid-raising means, still and condenser forming a vapor tight system when said valves are shut off.

5. An apparatus for cleaning materials by means of volatile cleaning liquids comprising a housing defining in its lower portion a vat for cleaning liquid, a container for materials to be

cleaned mounted in said housing, a tank adapted to receive cleaning fluid draining from said vat, a reservoir above said housing, means for raising cleaning liquid from said tank to said reservoir, means directing gravitational flow of cleaning liquid from said reservoir to the inside of said container, a still and condenser for cleaning liquid, and means adapted alternatively to direct gravitational flow of cleaning liquid from said reservoir directly to and through said still and condenser to said tank, by-passing said vat.

6. An apparatus for cleaning materials by means of volatile cleaning liquids comprising a liquid tight housing, an overflow for cleaning liquid part way of the height of said housing, defining in the lower portion of the housing a vat for cleaning liquid, a substantially cylindrical foraminous container for materials to be cleaned rotatable about a substantially horizontal axis and dipping for a part only of its diameter into said vat, a tank adapted to receive and store cleaning liquid overflowing from said vat, a reservoir above said housing, means for causing relatively slow rotation of said container, means for raising cleaning liquid from said tank to said reservoir and means directing gravitational flow of cleaning liquid from said reservoir against the outside of the unsubmerged portion of said container and through its perforations to its interior and thence to said vat, a still and condenser for cleaning liquid, and means adapted alternatively to direct gravitational flow of cleaning liquid from said reservoir directly to and through said still and condenser to said tank, by-passing said vat.

JOHN E. MARTIN.
